UNITED STATES PATENT OFFICE.

ABNER M. ROSEBRUGH, OF TORONTO, CANADA.

INDUCED-CURRENT TELEGRAPH.

SPECIFICATION forming part of Letters Patent No. 440,199, dated November 11, 1890.

Application filed February 3, 1886. Serial No. 190,715. (No model.)

To all whom it may concern:

Be it known that I, ABNER M. ROSEBRUGH, a subject of the Queen of Great Britain, residing at Toronto, in the Province of Ontario, Dominion of Canada, have invented certain new and useful Improvements in Induced-Current Telegraphs, of which the following is a specification.

This invention relates to improvements in methods and devices for signaling telegraphically by means of secondary electrical currents.

The object of this invention is twofold: First, to construct an improved secondary-current-telegraph system so that relays and sounders or their equivalent may be used, and, secondly, to combine said secondary-current-telegraph system with the ordinary Morse single or multiplex system, so as to be able to use the two simultaneously on the same wires. Any induced-current generator may be used, and the transmitting-key may be placed either in the local primary or in the secondary circuit. The receiving electro-magnet or relay is made with short coils and cores, the latter being by preference slightly magnetized.

Figure 1 represents the induced-current telegraph as arranged for single transmission. Fig. 2 represents an induced-current repeater. Fig. 3 represents a duplex receiver. Figs. 4 and 5 represent an induced-current telegraph combined with the ordinary Morse telegraph. Figs. 6 and 7 represent a magneto-electric generator and connections. Figs. 8, 9, and 10 represent the combination of telephonic with induced-current telegraphic apparatus.

In Fig. 1 A and B are two stations equipped with my induced-current apparatus. L is the line; I, the inductorium-transmitter; Re, the relay-receiver, and S the sounder. Rh is a rheotome in the primary circuit of the inductorium; LB, the local battery, and K the transmitter-key. The wires 8 and 9 shunt or short circuit the secondary coil of the inductorium, when the switch Sw makes contact with the point 21, and 15 and 18 are the wires of the sounder S, and LB the local battery. The battery is connected with the sounder on one side and with the armature of the relay on the other in the usual manner. 31 is

the front contact-point of the relay, and is connected with the other pole of the sounder by wire 18. 30 is a spring attached to the 55 armature-lever to give a yielding contact. M is an adjustable permanent magnet to magnetize the relay.

The operation is as follows: The primary circuit of the inductorium is closed by means 60 of the switch Sw. This puts the rheotome in action when the transmitting-key is depressed, and an undulatory induced current is sent to line. On reaching the distant relay its armature is caused to vibrate in proximity to 65 the core or cores of said relay, and this vibration closes the sounder-circuit and it remains closed while the vibrations continue, as the interruptions in the primary circuit of the transmitter are so rapid that the resulting secondary currents are practically continuous as long as the key remains closed to produce the signal. The lever of the distant sounder follows the movement of the home key the same as in ordinary Morse transmission; and this is accomplished by, first, making the transmitting-key a circuit-closer when the same is depressed, and, secondly, by connecting the sounder-circuit with the front local point of the relay and making the 80 contact a yielding one. By means of the switch Sw or its equivalent the resistance of the secondary coil of the inductorium is not interposed in the circuit, except during the transmission of a message. At other times it 85 is shunted or short-circuited. Short-circuiting or shunting of the secondary wire to remove the resistance thereof from the line when receiving may also be effected automatically by means of the transmitting-key, 90 as shown in Fig. 1, where the key K normally rests in contact with a line N, connected to the ground, and in Fig. 6, where the key K while a message is being received rests upon a contact 21 of the ground-line 8, or by means 95 of the sounder-lever in repeated circuits, as represented in Fig. 2, where the armature-lever 24 normally rests upon contact 25, connected directly with the ground through the wire 27 and one of the binding-posts of the 100 inductorium.

In long distances it is an advantage to divide the line into two or more circuits and using translators or repeaters. Thus in Fig.

- 2 I have shown my invention as applied to such use, and in said Fig. 2 O is a repeating-station. E is the wire east, and W the wire west. Re^2 is the relay of the wire east, and Re^2 the relay of the wire west. 10E and 11E are the primary wires of inductorium I' in the line east, and 10w and 11w are the primary wires of the inductorium I² in wire west. Rp' is a repeater from the east to the west circuit and Rp² a repeater from the west to the east circuit. The repeater is formed by the contact-points of the armature-lever 24 of the sounder S² and the front contact-point 26 of said sounder. These contact-points 25 and 26 control the primary circuit 10E and 11E of the inductorium. K' is a transmitting-key in the primary of the inductorium. Wire 27 and contact 25 are for shunting the inductorium, when necessary.
- 20 The operation of the repeater is as follows: An operator on, say, line west depresses the key of his transmitter and keeps it depressed. This charges the inductorium with rapidly-interrupted primary currents from the local battery, and this causes undulatory or to-and-fro induced currents to traverse the line. At the repeating-station this operates the relay Re^2 , the relay closes the sounder-circuit at the points 30 31, and the sounder S² in turn closes 25 the repeater-circuit at the points 25 26, and the repeater Rp² in turn closes the primary circuit of the inductorium I' on line east. This operates the inductorium on line east, and this in turn operates the receiver at the distant station on said line. At the repeating station the sounder-circuit is closed by the contact-points 30 and 31 of the relay, and the inductorium primary circuit is closed by the contact-points 25 and 26. By means of wire 30 27 the inductorium secondary coil is shunted from the circuit while receiving, which is an advantage by reducing the resistance of the line. Similarly, an operator on wire east can signal into wire west, and in this way any operator on either wire may put himself in communication with an operator on the other wire.
- 35 In the repeater-circuits I prefer to shunt or short-circuit the secondary of the inductorium to remove a resistance therefrom from the circuit by means of the armature-lever and back-stops 25 of the repeater, as represented in Fig. 2, the wire 27 being connected with the back contact-point 25 of the repeater.
- 40 50 It is an advantage in some cases to have the home-relay neutral to outgoing currents. This I accomplish by using compensating coils in the relay, as indicated by Fig. 3. Re is the relay, b the relay-coil, and 28 the compensating coil. The ends of the compensating coil are connected with the secondary of the inductorium. In this compensating circuit is inserted artificial resistance r and an electro-magnet EM, both preferably adjustable, the latter adjustable by a movable core, and these constitute the artificial line of the

ordinary differential relay. The artificial resistance is placed on the ground side i of coil 28, and may, if desired, be connected with the ground direct.

70 It will be understood that the current from the induction-coil divides, part passing through the coil b to line and part through the compensating coil 28 in an opposite direction, and through the magnet and resistance of the artificial line to ground in the usual manner.

75 In combining my induction-telegraph system with the Morse telegraph I adopt either of the following methods, namely: First, placing a differentially-wound receiver in the main line and bridging one of the coils with a condenser, as represented in Fig. 4, or, secondly, bridging an electro-magnet inserted in the main line with the induction-telegraph apparatus, as represented in Fig. 5.

80 In Fig. 4 D is a telegraph-line; K, a Morse key; R, a relay or telegraph-receiver; MB, a main-line battery, and Re a differentially-wound receiver, all in the main line. The bridging-circuit is arranged so as to shunt the Morse key, the telegraph-receiver, and one coil of the differentially-wound receiver, as represented. In the bridging-circuit are inserted a condenser, as indicated at F, and 85 an inductorium, as indicated at I, the local circuit not being represented.

90 In Fig. 5 D is a telegraph-line, and EM an electro-magnet inserted therein, which latter may be a telegraph-receiver. The induction-current-telegraph apparatus forms a bridge or shunt around this electro-magnet. Re is the induced-current receiver, I the inductorium, and F and F' the protecting-condensers. Of course any circuit-breakers or 95 any other electro-magnets in the main line must also be bridged by condensers. The operation of these arrangements will be readily seen from inspection, it being understood that the condensers are practically 100 opaque to the passage of the Morse galvanic signals, while the electro-magnets are opaque to the passage of the high-tension induced-currents from the inductorium. By this arrangement induced currents may be superimposed upon the Morse circuit without interference, and the two currents may be used simultaneously so as to constitute a multiple 105 telegraph.

110 The differentially-wound receivers, as well as the other receivers used for the induced-current telegraph, are preferably made with soft-iron cores, and said cores are magnetized by induction, as indicated at Re and M, Figs. 1 and 5, and the inductors are by preference 115 made adjustable.

120 When a magneto-electric generator is used instead of a rheotome and inductorium, the connections with the transmitting-key are 125 preferably those represented in Figs. 6 and 7. Dy is the generator, i is the pole to earth, and i' the pole to line. G is the ground, and

L the line. K is the transmitting-key, which is also an automatic shunt—that is, it shunts the generator when the key is open.

In Fig. 6 the coil of the generator is shunted so that no current goes to line when the key makes contact at 21 through wire 8, and in Fig. 7 the shunt is made by the switch S_w and wire 8 to ground.

I do not claim the arrangement of the condensers, as illustrated in Fig. 5, as such arrangement is covered by Patent No. 329,956, issued to me November 10, 1885.

In Fig. 8 I is an inductorium, with a rheotome R_h , and R_e an induced-current relay. I' is a supplemental inductorium, with its rheotome R_h' , and tel is a magneto-telephone. The inductorium I' is smaller than I, and the vibrator of the rheotome R_h' is shorter than that of rheotome R_h . By means of the smaller inductorium I' , I propose to send a current to line of a strength insufficient to effect the induced-current relays, but of sufficient strength to be heard in the magneto-telephones. By making the vibrators of the rheotomes of different lengths the signals of the different instruments may be differentiated by means of the telephone. All the transmitting-keys must of course be in the primary circuits of the induction-coils. The magneto-telephone may also be used as a receiver in the absence of the relay and sounder.

It will be seen that while there are two induced currents passing over the same line, the currents produced by one of the inductorium-transmitters are so weak that they do not operate the relay R_e , but will be heard in the telephone-receiver, while the stronger induced currents will operate the relay and be read from it or the sounder connected to it.

I also propose to combine induced-current-telegraph apparatus with the ordinary telephonic transmitting and receiving apparatus so that either may be used at pleasure, as represented in Fig. 9. Thus I is an inductorium; R_h its rheotome, and R_e the induced-current relay. L is the line, and G the ground.

tel is a telephone, and Tr a telephonic transmitter. S_w is a switch, by means of which either the telegraphic or the telephonic apparatus may be inserted into the circuit at pleasure. This combination may also be used when induced-current apparatus is used on the Morse telegraph-wires. In this case the rheotome and secondary-current relay may be

used as a telephone-signal, as represented in Fig. 10, D D' being the telegraph-wire, EM the electro-magnetic deflector in the main line, and L and G the two poles of the bridging telephonic circuit. Of course the Morse instruments in the line will be bridged by condensers, as represented in Fig. 5, and as covered by my patent, No. 329,956.

In this specification I refer only to the use of a rheotome for rapidly interrupting the primary circuit of the inductorium; but it is to be understood that any form of circuit-interrupter may be used for this purpose without departing from the spirit of this invention.

I claim—

1. In an induced-current telegraph, the combination, with the inductorium and circuit-closing key in the primary circuit thereof, a rheotome or its equivalent in said primary circuit, and a secondary circuit, of the inductorium in the line and a shunt around said inductorium, substantially as described.

2. In an induced-current telegraph, the combination, with the inductorium, rheotome, and primary-circuit key, of a relay, the armature of which forms part of the local circuit of the sounder and closes the same when on its front contact, substantially as described.

3. In an induced-current telegraph, the combination, with the relay adapted to respond to the induced currents, of an armature forming part of the local sounder-circuit when on its front contact, said armature being provided with a yielding or spring contact-piece, substantially as described.

4. In an induced-current telegraph, the combination, with the inductorium, the secondary of which is in line, of a primary containing a rheotome or its equivalent and key, a shunt in the main line around the inductorium, and a relay, the armature of which forms a part of the sounder-circuit when on its front contact and which is provided with a yielding contact-piece, substantially as described.

5. In an induced-current telegraph, the combination, with the relay and armature forming part of the sounder-circuit when on its front stop, of a sounder, the armature-lever of which forms part of the primary circuit of an inductorium in another line, substantially as described.

6. The combination, with a Morse telegraph, of an induced-current telegraph having an inductorium, the secondary of which is in the line and the primary of which includes a key and rheotome or its equivalent, a differential receiver in the main line, and a condenser bridging one of the coils of said receiver, substantially as described.

In testimony whereof I have signed my name to this specification in the presence of two subscribing witnesses.

A. M. ROSEBRUGH.
